UNITED STATES PATENT OFFICE.

ADOLPHUS S. DENNIS, OF LAKWOOD, OHIO, ASSIGNEE, BY MESNE ASSIGNMENTS, TO
UNDERWOOD COMPUTING MACHINE COMPANY, OF NEW YORK, N. Y., A CORPORA-
TION OF NEW YORK.

COMBINED TYPE-WRITING AND COMPUTING MACHINE.

1,317,965.

Specification of Letters Patent.

Patented Oct. 7, 1919.

Application filed August 3, 1912. Serial No. 713,026.

To all whom it may concern:

Be it known that I, ADOLPHUS S. DENNIS, a citizen of the United States, residing at Lakewood, in the county of Cuyahoga and 5 State of Ohio, have invented certain new and useful Improvements in Combined Type-Writing and Computing Machines, of which the following is a specification.

This invention relates to power-driven computing mechanism, and particularly to machines in which relative step-by-step denominational movement occurs between a master wheel and a set of computing wheels.

The invention is shown as applied to an 15 Underwood front-strike typewriting machine, and embodies improved means for causing the master wheel to be rotated by power at the operation of the numeral keys of the typewriter. The computing wheels 20 are, for convenience, shown connected to the typewriter carriage for step-by-step denominational movements; although the master wheel could be arranged to travel; and the invention is also applicable to other forms 25 of computing machines.

The principal object of the invention is to provide a mechanism speedy, simple, inexpensive, reliable, and not apt to get out of order, for promptly connecting the source 30 of power to the master wheel, to drive the latter independently, as the numeral keys are operated, varying amounts corresponding to the particular keys actuated.

In the preferred form of the invention, 35 nine independent clutches (all normally open) are arranged loosely upon a power shaft, and from these clutches extend nine separate trains of connections to the numeral keys of the typewriter, so that any key may close 40 its clutch. Whenever a clutch is closed by associated key, a mutilated gear which is connected to the clutch is caused to rotate with the shaft so as to rotate the master wheel of the computing mechanism. The 45 mutilated gears have graded numbers of teeth corresponding to the value of the associated numeral keys, so that the master wheel is rotated an extent determined by the key operated. Each clutch tends normally to 50 close, but is restrained from doing so by means of a dog, and the dog is released by

the depression of a numeral key. The action of the clutch is very prompt, so that the power shaft is connected to the master wheel and rotates the same as far as required without delay; and the master wheel may, in some cases, finish its rotation before the numeral key is fully depressed. Preferably, the numeral key sets the computing train into operation at the beginning of the down 60 stroke of the key, so that ample time may be allowed for the rotation of the master wheel before the carriage of the typewriter begins its feeding movement, which, of course, does not usually begin until after the key starts 65 its own return or upward movement.

The interval during which the master wheel may be rotated preferably includes the larger part of the time during which the key is making its down stroke, the time during 70 which the finger of the operator makes an involuntary pause at the conclusion of the down-stroke, and also a portion of the time occupied in the return stroke of the key; that is, until the typewriter carriage is liberated 75 and begins to travel. This interval, from near the beginning of the down-stroke of the key until the carriage gets under way, is sufficient for the rotation of the master wheel through the maximum of nine points, especially where the drive shaft is rotated at 80 high speed, as is practicable in the present invention.

As soon as any key, during its down-stroke, effects the closing of its associated 85 clutch, a disconnection is automatically effected between the key and the clutch, so that the clutch may be automatically arrested or opened (independently of the key) at the conclusion of a single revolution thereof, 90 which may even happen before the key finishes its down-stroke, if the drive-shaft is rotating at very high speed. At any rate, the mutilated gear will be prevented from rotating more than one revolution with the 95 power shaft, even if the key should be held depressed longer than is necessary. Upon release of the key, connection is automatically re-established between the key and the clutch mechanism, said member itself becoming automatically released from the key, so that 100 the remainder of the cycle of operations of

the computing mechanism is automatic and rapid. It is found in practice that the keys may be operated at very high speed, without any liability of any erroneous or faulty action of the computing mechanism.

The mutilated gears are preferably normally arranged in such position that when one starts to rotate, it will mesh with a corresponding gear on a shaft which is positively geared to the master wheel, thus insuring a positive connection between the numeral key control and the master wheel. The clutch by which the rotation of the mutilated gears is controlled may positively seize by means of abutting members. Preferably the clutch normally tends to seize, but is normally held against seizing by a member moved to ineffective position by the operation of a numeral key.

Other features and advantages will hereinafter appear.

In the accompanying drawings—

Figure 1 is a side elevation.

Fig. 2 is a section transversely of the machine.

Fig. 3 is a front view.

Fig. 4 is a plan view of the connections between the numeral keys and the drive shaft.

Fig. 5 is a diagrammatic view, showing the relation of the different numeral gears to the drive-shaft.

Figs. 6 and 7 are details of the connections between the numeral keys and the clutches.

Fig. 8 shows a clutch in its normal position.

Fig. 9 shows a clutch just after the moment of seizing.

Fig. 10 is a vertical section through a clutch and the main drive-shaft of the computing mechanism.

Alphabet keys 1 and numeral keys 2 depress levers 3 to vibrate bell cranks 4, which swing type bars 5 up against a platen 6. The latter is mounted in a carriage 7 propelled by the usual spring barrel, (not shown). The carriage has a rack 8 to mesh with a pinion 9, which is connected to an escapement wheel 10. Dogs 11, 12 control the movements of said escapement wheel. Each type bar has a heel 13, so that it may press rearwardly a universal bar 14, which operates the dogs 11, 12, whereby letter feeding movements of the carriage are caused at the type strokes, as is usual in an Underwood front-strike typewriting machine. It will be noted that the typewriter carriage is fed forward on the return stroke of the type keys.

A separate train of mechanism connects each numeral key to the power-driven means which turns master wheel 16, so that at the operation of the numeral key, the master wheel is positively turned. Said train includes in each instance a rock arm

17 arranged to be operated by the lever 3 of 65 the particular numeral key; which rock arm 17 is fast on a shaft 18 carrying rock arm 19. Said rock arm 19 is arranged on the depression of its key to cause a clutch 22 to seize by swinging a bar 20 out of the path of 70 a pivoted dog 21 in said clutch 22, so that a light spring 23 will cause said clutch to seize the power-driven shaft 24, and through a mutilated gear 25 on said clutch, said shaft 24 turns master wheel 16. 75

The connections between said master wheel and each of said mutilated gears include a gear 26 aligned with each of said mutilated gears and fast on a main computing shaft 27, which shaft carries bevel gear 28 meshing with bevel gear 29 on shaft 30, which shaft 30 in turn carries a bevel gear 31 meshing with a bevel gear 32 fast on the master wheel shaft 33. 80

The clutch 22 seizes the power-driven 85 shaft 24 by means of an arm 34 forming a continuation of dog 21, which is normally pressed inward by means of the light spring 23 so that the hook 36 on said arm will intercept the teeth 37 on said power-driven 90 shaft. As the numeral key 2 is depressed, it swings rock arm 19 so that it strikes bar 20, and it will be noted that the pawl 38 on the end of said rock arm 19, which is the part that actually contacts with said bar 20, will 95 engage said bar at its end and only momentarily, that is, until pawl 38 slips off from bar 20, as shown in dotted lines at Fig. 6, permitting the key to finish its printing stroke, and releasing bar 20 from the control 100 of the key; and a spring 39 will at once return said bar 20 after it is so released so that the bar 20 is immediately returned into the path of dog 21, independently of the key. When the clutch 22 has completed one revolution, said clutch will accordingly be automatically opened or released by said dog striking said bar 20. On the return stroke 105 of the key, the pawl 38 may yield or slide backward by its slots 40 on pins 41 to pass 110 said bar 20, and a spring 42 draws it again into effective position when it has passed said bar. The arm 17 follows the key lever 3 on its return stroke under the torque of coil spring 35. Regarding pawl 38, the reason 115 that it slips off from 20 when a key is going down, is because 20 descends in a vertical path, whereas 38 moves diagonally downward and backward about pivot 18, until 38 draws back off from 20, as shown by the dotted lines, thus interrupting the connection 120 between the key and the computing train.

The mutilated gear 25 which is controlled by the clutch, carries teeth 43 proportionate in number to the numeral key operated. 125 As shown in Fig. 8, said mutilated gear carries three teeth and is controlled by the numeral key "3". As shown in Fig. 10, said

mutilated gear 25 is attached to the cup member 44 of said clutch 22 by means of screws 45, so that it moves as a unit therewith, and said clutch may include a cover 5 46 for its face.

The power for driving said shaft 24 may be a constantly driven electric motor 47 geared directly thereto so as to obtain a speed, preferably sufficient to complete the 10 computation as soon as the numeral key reaches its lowest point of depression.

It will be noted that the bar 20 is arranged to be operated by the numeral key very early in its depression, and that thereby 15 the touch of the keys need be very slightly affected by the computing mechanism. To further lighten the touch of the keys, the lever 3 is preferably arranged to move the rock arm 17 by means of a roller 48 fast 20 on a pin 49 on said arm.

The master wheel 16 is arranged to register with and turn *serially* the dial or computing wheels 50 of a totalizer 51, and for this purpose, the totalizer 51 may be arranged 25 to travel on rollers 52 across the front of the machine, as shown in Fig. 2, step-by-step with the typewriter carriage. For this purpose there preferably extends from the typewriter carriage an arm 53 30 which is arranged to engage said totalizer so that it will always travel with said typewriter carriage.

The dial wheels 50 need not be directly engaged by the master wheel 16, but are 35 preferably operated by said master wheel through intermediate gears 54 and idle gears 55, there being one of said intermediate and idle gears for each dial wheel.

It will be seen that when any numeral 40 key is depressed, it causes its train of mechanism to positively seize the power-driven shaft 24 and thus causes this shaft to positively turn the master wheel. The whole load of operating the computing mechanism, 45 except for tripping the clutches, is taken care of by the power-driven shaft, and therefore, the touch of the numeral keys may be exceedingly light. It will be seen that each operation of the computing mechanism 50 returns the parts to normal idle position, without reversing its movement of any part except the rock arms.

In Fig. 5 is diagrammatically shown the arrangement of mutilated gears for each of 55 the numeral keys from "1" to "9", with reference to the main computing shaft 27. It will be noted that while the mutilated gears normally have their teeth clear of the gears 26, the first tooth on each mutilated gear is 60 arranged to almost immediately mesh with the gear 26 on the main computing shaft 27 so as to obtain a prompt action of the computing mechanism. This renders it impossible for the machine to be operated so fast

that the master wheel will still be turning 65 when the typewriter escapement feeds the carriage 7 and totalizer 51 to the next letter space.

Variations may be resorted to within the scope of the invention, and portions of the 70 improvements may be used without others.

Having thus described my invention, I claim:

1. In a combined typewriting and computing machine comprising a set of type-controlling number keys and power-driven actuating mechanism controlled thereby, said actuating mechanism including a set of differentiated valuating elements, one for each key, a driving shaft and a set of normally ineffective clutches, one for each valuating element, each capable of being rendered effective to connect its respective valuating element to said shaft, the combination with one of said keys and the clutch associated with the corresponding valuating element, of a clutch-controlling key-connection normally effective on operation of said key to cause said clutch to connect said valuating element to said shaft for a predetermined cycle of movement, said connection including disabling means for breaking the co-operative relation between the key-controlled parts and the clutch-operated parts when said clutch has been thus rendered effective and prior to the return of said key to normal position, the relation between said clutch and parts of said key connection, when thus disabled, being such that said key, and the parts connected therewith, may be caused to complete their movements and return to normal position free from control by said clutch-operated parts, said relation also being such that said key, and key connected parts, are rendered incapable of initiating a second cycle of movement of said clutch-operated parts prior to the return of said key to normal position.

2. In a combined typewriting and computing machine comprising a set of type-controlling number keys and power-driven actuating mechanism controlled thereby, said actuating mechanism including a set of differentiated valuating elements, one for each key, a driving shaft and a set of normally ineffective clutches, one for each valuating element, each capable of being rendered effective to connect its respective valuating element to said shaft, the combination with one of said keys and the clutch associated with the corresponding valuating element, of a clutch-controlling key-connection normally effective on operation of said key to cause said clutch to connect said valuating element to said shaft for a predetermined cycle of movement, said connection including disabling means for breaking the co-operative relation between the key-con-

- trolled parts and the clutch-operated parts when said clutch has been thus rendered effective and prior to the return of said key to normal position, the relation between said clutch and parts of said key connection, when thus disabled, being such that said key, and the parts connected therewith, may be caused to complete their movements and return to normal position free from control by said clutch operated parts, said relation also being such that said key, and key connected parts, are rendered incapable of initiating a second cycle of movement of said clutch operated parts prior to the return of 15 said key to normal position, said key-connection also including means for reestablishing the operative relation between said key and said clutch on a return of said key to normal position.
3. In a combined typewriting and computing machine comprising a set of type-controlling number keys and power-driven actuating mechanism controlled thereby, said actuating mechanism including a set of differentiated valuating elements, one for each key, a driving shaft and a set of normally ineffective clutches, one for each valuating element, each capable of being rendered effective to connect its respective valuating element to said shaft, the combination with one of said keys and the clutch associated with the corresponding valuating element, of a clutch-controlling key-connection normally effective on operation of said key to cause said clutch to connect said valuating element to said shaft for a predetermined cycle of movement, said connection including mutually coöperative elements 20 normally in engaging relation, which are caused to be moved out of such engaging relation as a part of the operation of said key-connection by said key to render said clutch effective, thus disabling said key-connection prior to the return of the operated key to its normal position, said connection also including means for moving one of said parts when disconnected to a position such as to prevent reengagement with the other without first returning said key to normal position, said disengaging parts being provided with means for reestablishing engaging relation on return of said key-controlled parts to normal position, the relation between said clutch and parts of said key connection, when thus disabled, being such that said key, and the parts connected therewith, may be caused to complete their movements and return to normal position free from control by said clutch operated parts prior to the return of said key to normal position.
4. In a combined typewriting and computing machine comprising a set of type-controlling number keys and power-driven actuating mechanism controlled thereby, said actuating mechanism including a set of differentiated valuating elements, one for each key, a driving shaft and a set of normally ineffective clutches, one for each valuating element, each capable of being rendered effective to connect its respective valuating element to said shaft, the combination with one of said keys and the clutch associated with the corresponding valuating element, of a clutch-controlling mechanism, 25 said mechanism comprising a controlling element normally effective to maintain such clutch ineffective and its valuating element in normal position, an operating element connected to said key and normally in engaging relation with said controlling element, so that by operating said key said controlling element may be moved to render

said clutch effective, the relation between said controlling element and said operating element being such that they will move out of engaging relation during the operation 5 of said mechanism, to render said clutch effective and before the return of said key to its normal position, and means for restoring said controlling element, when thus disconnected to its normal position, so as to 10 render said clutch ineffective at the completion of its cycle of movement and again maintain said valuating element in its normal position, the relation between said clutch and its controlling mechanism, 15 when thus disabled, being such that said key, and its operating element, may be caused to complete their movements and return to normal position free from control by said clutch operated parts, said relation 20 also being such that said key, and its operating element, are rendered incapable of initiating a second cycle of movement of said clutch operated parts prior to the return of said key to normal position. 25 6. In a combined typewriting and computing machine comprising a set of type-controlling number keys and power-driven actuating mechanism controlled thereby, said actuating mechanism including a set of 30 differentiated valuating elements, one for each key, a driving shaft and a set of normally ineffective clutches, one for each valuating element, each capable of being rendered effective to connect its respective valuating element to said shaft, the combination 35 with one of said keys and the clutch associated with the corresponding valuating element, of a clutch-controlling mechanism, said mechanism comprising a controlling element normally effective to maintain said 40 clutch ineffective and its valuating element in normal position, an operating element connected to said key and normally in engaging relation with said controlling element, so that by operating said key said controlling 45 element may be moved to render said clutch effective, the relation between said controlling element and said operating element being such that they will move out of engaging relation during the operation of said 50 mechanism, to render said clutch effective and before the return of said key to its normal position, means for restoring said controlling element, when thus disconnected, to its normal position, so as to render said 55 clutch ineffective at the completion of its cycle of movement and again maintain said valuating element in its normal position, the relation between said clutch and its controlling mechanism, when thus disabled, 60 being such that said key and its operating element may be caused to complete their movements and return to normal position free from control by said clutch operated parts, said relation also being such that said 65 key and its operating element are rendered incapable of initiating a second cycle of movement of said clutch operated parts prior to the return of said key to normal position, and means for reestablishing the 70 normal engaging relation between said controlling element and its operating element on a return of said key to its normal position.

ADOLPHUS S. DENNIS.
